OTIS G. CLARK, OF TROY, AND DANIEL D. BUCKLIN, OF LANSINGBURG,
EXECUTORS OF NICHOLAS S. VEDDER, DECEASED, AND TOBIAS S. HEIS-
TER, OF LANSINGBURG, NEW YORK; SAID HEISTER ASSIGNOR TO SAID
CLARK AND BUCKLIN AS EXECUTORS.

DESIGN FOR A COOKING-STOVE.

SPECIFICATION forming part of Design No. 11,883, dated July 20, 1880.

Application filed June 14, 1880. Term of patent 3½ years.

To all whom it may concern:

Be it known that NICHOLAS S. VEDDER, deceased, late of the city of Troy, in the county of Rensselaer and State of New York, and TOBIAS S. HEISTER, a resident of Lansingburg, in said county and State, did jointly invent and produce a certain new and original Design for Cooking-Stoves; and that OTIS G. CLARK, residing in the aforesaid city of Troy, and DANIEL D. BUCKLIN, residing in Lansingburg, aforesaid, are the executors of the last will and testament of said NICHOLAS S. VEDDER, deceased; and we, the said OTIS G. CLARK, DANIEL D. BUCKLIN, and TOBIAS S. HEISTER, hereby declare that the following is a specification of said new design, reference being had to the accompanying print, cut, or engraving representing the same.

One part of this invention is the design of the panel ornament A, composed of the central medallion, b, representing an ornamented female human head, the panel c, surrounded by the frame d, having the laterally-extended and scroll-ornamented lower portion, e, the side scrolls, f, and the reversely-inclined top portion, g, having the projecting corner ornaments, h, central ornament, i, and incut ornamentations, j, all shaped and arranged together so as to present the appearance represented in the aforesaid cut.

Another part is the design for the panel-border K, composed of the inner bead, l, having the truncated corners m and scalloped edging n, the outer bead, o, intermediate matted ground, p, compound scroll ornaments g in the corners, and the diamond-like ornaments r, all shaped and arranged together so as to appear as represented in the aforesaid print.

Another part is the design for the oven-door, 40 consisting of the panel ornament A, composed as above described, and centrally arranged on the panel S, and the compound border K of said panel, composed as above specified, and the whole combination presenting the appearance represented in the aforesaid engraving.

Another part is the design for the closet-

door, consisting of the central medallion, b', mat c', and surrounding frame d' on the panel t, and the ornamental border K', composed of the parts l', m', n', o', p', q', and r', all shaped and arranged together so as to present the appearance represented in the accompanying cut.

Another part is the design for the door or panel at the end of the fire-box, consisting of the medallion b² only on the panel u and the ornamental border composed of the parts l², m², n², o², p², q², and r², all shaped and arranged so as to appear as represented in the aforesaid print.

What is claimed as the joint invention and production by the aforesaid NICHOLAS S. VEDDER, deceased, and TOBIAS S. HEISTER, aforesaid, is—

1. The design for the panel ornament A, 65 composed of the parts b, c, d, e, f, g, h, i, and j, as shown and described.

2. The design for the panel-border K, composed of the parts l, m, n, o, p, q, and r, as shown and described.

3. The design for the oven-door, consisting of the panel S, compound central ornament, A, and compound border K, all composed and arranged as shown and described.

4. The design for the closet-door, consisting 75 of the parts b' c' d' t and compound border K', as shown and described.

5. The design for the door or panel at the end of the fire-box, consisting of the parts b², u, l², m², n², o², p², q², and r², as shown and described.

In testimony whereof we hereunto set our hands, in the presence of two subscribing witnesses, this 10th day of June, 1880.

OTIS G. CLARK,
DANIEL D. BUCKLIN,
Executors of Nicholas S. Vedder, deceased.
TOBIAS S. HEISTER.
